(57) **CLAIM**

The ornamental design for a damper extrusion, as shown and described.

DESCRIPTION

FIG. 1 is a top perspective view of a damper extrusion showing my design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is an enlarged bottom perspective view thereof.

The broken lines in the drawings illustrate portions of the damper extrusion that form no part of the claimed design. The damper extrusion is shown with a symbolic break in its length. The appearance of any portions of the damper extrusion between the break lines forms no part of the claimed design.
